UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 31,069, dated June 27, 1899.

Application filed June 2, 1899. Serial No. 719,151. Term of patent 7 years.

To all whom it may concern:

Be it known that I, WILLIAM C. CODMAN, of Providence, in the county of Providence and State of Rhode Island, have invented and produced a new and original Design for the Handle of a Spoon, Fork, or Similar Article, of which the following is a specification, reference being had to the accompanying drawings, forming part thereof.

10 Figure 1 is a view of the obverse side of a handle, and Fig. 2 a view of the reverse side of a handle, showing my design.

The leading features of my design consist in the raised and diagonally-beaded marginal border of the stem of the handle, terminating in scrolls, the raised and diagonally-beaded marginal scrolls on the opposite sides of the blade of the handle, and the scrolls forming the margin of the end of the blade, ornamented with floral rosettes on the obverse side of the handle.

In the drawings, A indicates the bowl of a spoon, the tines of a fork being indicated in broken lines, B the stem of the handle, and 25 C the blade of the handle. At the junction of the handle with the bowl of a spoon or similar article the stem increases in width and is ornamented by the foliated scrolls *a a*, inclosing a floral ornament which on the reverse 30 of the handle extends partly over the bowl. From the scrolls *a a* the stem of the handle curves slightly inward to the narrow part of the stem and then curves outward to the junc-

tion of the stem with the blade of the handle. The edges of the stem are ornamented with 35 the raised and diagonally-beaded margins *bb*, terminating at the junction of the blade with the handle in the scrolls *cc*. On the obverse side of the handle the floral ornament *d* extends from the scrolls *cc* downward. On the 40 reverse side of the handle the floral ornament *d* is omitted. The raised diagonally-beaded scrolls *ee* on the margins of the blade *C* are separated from the scrolls *cc* on the obverse side by the floral rosettes *ff* and on the reverse side by the scrolls *f' f'*. The margin of the upper end of the blade *C* of the handle is ornamented by the raised scrolls *gg* extending along each side and supporting the arched crest ornament *h*, which forms the end 45 50 of the handle. On the obverse side this upper end of the blade is ornamented with the floral rosettes *ii*. The spaces between the ornamentations form convex panels.

Having thus described my invention, what 55 I claim as new, and desire to secure by Letters Patent, is—

The design for the handle of a spoon, fork or similar article herein shown and described.

In witness whereof I have hereunto set my 60 hand.

WILLIAM C. CODMAN.
